WILLIAM H. ANDREWS, OF NEW HAVEN, CONNECTICUT, ASSIGNOR
TO BURTON MALLORY, OF SAME PLACE.

Letters Patent No. 88,113, dated March 23, 1869.

IMPROVEMENT IN DOOR-KEYS.

The Schedule referred to in these Letters Patent and making part of the same.

To all whom it may concern:

Be it known that I, WILLIAM H. ANDREWS, of New Haven, in the county of New Haven, and State of Connecticut, have invented a new Improvement in Door-Keys; and I do hereby declare the following, when taken in connection with the accompanying drawings, and the letters of reference marked thereon, to be a full, clear, and exact description of the same, and which said drawings constitute part of this specification, and represent in—

Figure 1, a side view;

Figure 2, an edge view; and in

Figure 3, a side view of the key extended.

This invention relates to an improvement in keys, such as are commonly known as store-door keys.

These keys, as it is well known, are necessarily long, usually from six to eight inches, and are therefore exceedingly inconvenient to carry about the person.

The object of this invention is to reduce the length of the key when it is removed from the lock, for the convenience of the person carrying the key; and

The invention consists in forming the bit upon the shank, or spindle, in the usual manner, the said spindle being about half the usual length, and into the back of the said spindle I cut a groove longitudinally, and into the outer end of the groove I pivot a handle, formed from metal, so as to turn over and set into the groove cut in the back. This handle, turned from the groove outward, extends the key to the length required, and, when closed, contracts the key, so as to reduce it to about half its usual length.

In order to the clear understanding of my invention, I will fully describe the same, as illustrated in the accompanying drawings.

A is the bit of the key, fixed, or formed upon a spindle, B, in the usual manner, the said spindle being about half the usual length. I then groove the spindle upon its back, as seen in fig. 2, to about the depth denoted by the broken line in fig. 3.

Into the outer end of this groove I hinge, or pivot an extension, C, the said extension being of such form that it will fold into the back of the spindle, as seen in figs. 1 and 2, and so as to be easily turned therefrom, to extend the key, as seen in fig. 3.

In its contracted state it becomes a little larger than the common door-key; but extended, it is of the usual length of keys of this class.

I do not broadly claim a key constructed so as to fold within a case, or handle, as such, I am aware, is not new, and may be found in the drawings in the patent of T. A. Auberlin, April 17, 1866.

Having fully described my invention,

What I claim as new and useful, and desire to secure by Letters Patent, is—

A door-key, consisting of the bit A, and spindle B, hinged thereto, the said spindle being grooved, so as to receive the extension C, the whole constructed so as to operate substantially as set forth.

WM. H. ANDREWS.
